UNITED STATES PATENT OFFICE

2,063,646

COOLING UNIT

Harry A. Whitesel, Fort Wayne, Ind., assignor to
General Electric Company, a corporation of
New York

Application June 27, 1933, Serial No. 677,870

12 Claims. (Cl. 62—126)

My invention relates to cooling units for refrigerating systems.

It has been found that when meat and other similar perishable food are to be kept in condition for sale and use, such as in meat markets and restaurants, certain narrow ranges of temperature must be maintained in order to preserve the foods satisfactorily for a maximum length of time. It is essential that the temperature throughout the chamber be uniform. Cooling units with forced air circulation are employed in installations of this type and are preferably operated upon the well-known defrosting cycle. It is often difficult however, to maintain the proper range of temperatures in the installations because the temperature of the cooling units is not uniform throughout, so that the air circulated through the cooling unit is not cooled uniformly. This lack of uniformity of the temperature of the surface of the cooling unit is particularly noticeable when the defrosting cycle is employed, since it is necessary that the entire evaporator should warm up to a temperature above 32° F. in order to completely defrost the evaporator before the operation of the refrigerating machine is started again. When the evaporator is not of a uniform temperature throughout, it is necessary that the control device should operate over a wide range in order to insure complete defrosting, and it is evident that when such a wide range of temperature is employed there will be a wide range of average temperature in the chamber to be cooled. This results in variations in temperature in the cabinet or other chamber to be cooled, which may result in spoilage of food.

Accordingly, it is an object of my invention to provide a cooling unit for refrigerating systems which can readily be maintained at a uniform temperature throughout, and in this way maintain a uniform temperature throughout the chamber to be cooled.

Another object of my invention is to provide a cooling unit for refrigerating systems provided with forced air circulation which is of rugged construction and highly efficient in operation.

Further objects and advantages of my invention will become apparent as the following description proceeds, and the features of novelty which characterize my invention will be pointed out with particularity in the claims annexed to and forming a part of this specification.

For a better understanding of my invention reference may be had to the accompanying drawing in which Fig. 1 is a side elevation of a refrigerating system provided with a cooling unit em-

bodying my invention; Fig. 2 is a perspective view, partly broken away, of the cooling unit shown in Fig. 1; Fig. 3 is a detailed sectional view of the header and injector construction; and Fig. 4 is a detailed sectional view of the cooling coil and 5 brine container construction.

Referring to Fig. 1, I have shown a refrigerating system including a housing 10 mounted on a base 11 which is a removable top of a refrigerator cabinet or other chamber to be cooled. Within the 10 housing 10 is arranged a motor and compressor casing 12, a refrigerant condenser 13, and a motor 14 having a fan 15 driven thereby for cooling the casing 12 and the condenser 13. Refrigerant compressed in the casing 12 is liquefied in the condenser 13 and flows to a flow-control device or float valve 16 mounted on the top 11 outside the housing 10. A cooling unit 17 embodying my invention is suspended on legs 18 from the top 11, and the liquid refrigerant flows thereto through a 20 conduit 19. The liquid is vaporized by absorption of heat and is withdrawn from the cooling unit 17 through a conduit 20.

The cooling unit as constructed in accordance with my invention comprises an evaporator including a plurality of tubes arranged for forced circulation of refrigerant therein and surrounded by flat containers filled with a negative heat storage substance, such as a glycerine or brine solution. The evaporator is enclosed in an open-ended casing at one end of which is detachably secured a fan for circulating air through the casing.

Referring now particularly to Fig. 2, as an example of one manner of carrying out my invention, I have shown a cooling unit including an evaporator comprising an upper header 21 connected by a vertical conduit 22 to a lower header 23, and a plurality of looped tubes or refrigerant-circulating members 24 connected between the 40 upper and lower headers. In order to produce circulation of refrigerant within the evaporator, I provide an injector system for causing the refrigerant to flow upward through the looped tubes 24 to the upper header 21 and to return 45 through the vertical conduit 22 to the lower header. This injector system includes a conduit 25 entering the lower header and extending therethrough past the openings of the tubes 24 and branch conduits or injector tubes 26 which 50 extend into the lower ends of the looped tubes, the end of the conduit 25 being closed. This construction is clearly shown in Figs. 2 and 3 which also show the manner of connecting the looped tubes to the headers. As can be seen, 55

the injector tubes 26 extend a substantial distance into the lower end of the looped tubes 24, and when a mixture of gaseous and liquid refrigerant formed when liquid refrigerant passes 5 through the float valve is forced out through the injector tubes, it will cause a flow of the refrigerant within the tube 24 toward the upper header and promote vaporization of liquid refrigerant in the tubes. The header 21 is maintained partially 10 filled with liquid refrigerant and to a level indicated at 21a above the upper openings of the tubes 24 and the conduit 22. Any refrigerant which is vaporized due to the absorption of heat will be carried along by the flow in the tubes 24 15 and will collect in the upper header, from which it is withdrawn through a suction connection 27 by the compressor. The rapid circulation of liquid refrigerant which carries the vaporized refrigerant quickly to the upper header insures 20 a uniform temperature and heat-absorbing capacity throughout all of the tubes of the evaporator, since pockets of vapor cannot remain within the liquid for any substantial time to act as insulating layers to prevent uniform absorption of 25 heat, and since the agitation due to circulation and the presence of vapor injected into the looped tubes prevents any superheating of the liquid refrigerant which would also vary the rate of absorption of heat. As is evident from Fig. 1, 30 the tubes 24 slope upwardly at all points and, since the liquid level in the header is maintained above the upper ends of the tubes 24 and the opening of the conduit 22, natural circulation of the liquid refrigerant through the evaporator 35 will continue during the inactive part of the operating cycle during which refrigerant is not being injected into the evaporator. This circulation, as is well understood in the art, is produced by the upward movement of vaporized gas within 40 in the evaporator. Since more vapor will be formed in the tubes 24 by the absorption of heat than in the conduit 22, there will be a tendency for the refrigerant to circulate upward through the tubes 24 and downward through the conduit 22. 45

On either side of each looped tube 24 I provide sheets 28 joined thereto, which extend the effective heat-absorbing surface of the tubes 24. In the preferred embodiment illustrated and 50 clearly shown in Fig. 4, I fold the edges of one of the sheets 28 about the other and join them, as indicated at 29, to form a sealed container or tank 30. I prefer to seal the joints 29 at the edges of the sheets 28 and attach the tubes 55 24 to these sheets by brazing, but this may be done in any other suitable manner. This container is filled with a negative heat storage substance 30a such as a glycerine or brine solution, or any other suitable liquid, which will be frozen 60 during the operation of the refrigerating mechanism and will be melted during the idle periods of the mechanism by the absorption of heat from the chamber to be cooled. The use of such a solution provides an additional storage capacity or "fly wheel" effect, since sufficient heat 65 must be absorbed to melt the frozen solution before the temperature of the evaporator can be appreciably raised. In order to still further increase the effective heat-absorbing surface of the 70 evaporator units comprising the looped tubes 24 and the surrounding containers 30, I weld sheets of metal, stamped to form zig-zag fins 31 on both sides of each container, the fins 31 extending horizontally. This arrangement of the tubes 75 within the containers and of the fins secured to

the containers provides an efficient cooling unit for use where rapid cooling of the circulating air is desired in addition to storage of heat-absorbing capacity. It will be observed that since the tubes 24 are in contact with the sides 5 28 of the containers 30, heat may be transferred from the fins directly through the containers to the refrigerant within the tubes, which avoids the delay in the transmission of heat occurring 10 when the brine solution or other fluid completely 15 surrounds the refrigerant tubes. These fins are arranged in staggered relation so that the attached portion 32 on one side of each tank will be opposite the raised portions 33 of the zig-zag fins on the other side of the tank and I arrange 20 the fins on the adjoining tanks so that the raised portions 33 on one tank will be opposite the attached portions 32 on the other tank. This effects a more uniform distribution of the heat-absorbing areas between the tanks. All of the 25 fins 31 are parallel and extend horizontally along the tanks. The evaporator is enclosed in a casing 34 which constitutes an air duct and which includes an upper plate 35, a lower plate 36, and side plates 37, which are joined together at their 30 edges. The upper header extends above the upper plate 35 and beyond both sides of the casing 34. Each evaporator unit is securely held in place between the upper and lower plates. This is accomplished by forming indentations 38 in the 35 upper and lower plates transversely of and extending toward the evaporator units. Each container is provided with a rib 39 extending around the periphery thereof and formed when the sides of the tank are joined at 29 by folding the edges 35 of the plates 28 over each other. These ribs are fitted into slots 40 cut in the indentations 38 and are welded or otherwise secured to the upper and lower plates around these slots, as indicated at 41. This method of construction provides a 40 rigid unit which will withstand large stresses. Any moisture which is condensed on the evaporator and flows to the bottom plate 36, will be drained from the bottom plate through a pipe 42 provided at the rear thereof. 45

In order to provide a circulation of air through the cooling unit longitudinally of the heat-absorbing fins, I provide a motor-driven fan 43 mounted on an end plate 44 of the casing 34, which impels the air from the fan through the 50 cooling unit to the opposite open end thereof. The fan 43 and a driving motor 45 for driving the fan are secured to the end plate 44 on radial struts 46, the end plate being provided with a cylindrical fan housing 47 having perforations 48 to permit passage of air therethrough. The end plate 44 is provided with side flanges 49 engaging the side plates 37 of the casing on the outer sides thereof, and the end plate rests on the bottom plate 36 adjacent an upturned flange 50 which 55 prevents the end plate from sliding off the bottom plate. An inturned flange 51 at the upper edge of the end plate 44 rests against the upper header 21 and closes the casing along the upper edge thereof. The side flanges 49 are detachably 60 secured to the side plates 37 by thumb screws 52 which may quickly be released to permit removal of the end plate from the cooling unit. By this arrangement, when it is desired to inspect or repair either the cooling unit or the fan motor, 65 it is easy to remove the motor and driving fan.

In the operation of the refrigerating system shown in Fig. 1, refrigerant compressed by the compressor within the casing 12 flows to the condenser 13 where it is liquefied and then collects 70 75

in the float chamber 16. When a sufficient quantity of liquid refrigerant has collected, the float valve operates to allow the refrigerant to enter the conduit 19. The liquid refrigerant is partially vaporized in passing through the valve and the mixture of liquid and vapor refrigerant flows through the conduit 19 and is injected through the tubes 26 into the tubes 24 and induces circulation of refrigerant through the 10 looped tubes to the upper header and back to the lower header. The vaporized refrigerant introduced through the injector tubes together with the circulation produced thereby prevents any superheating of the liquid refrigerant in the 15 evaporator since a liquid refrigerant boils readily in the presence of its vapor. The rapid circulation together with the absence of superheating of the liquid refrigerant assures a uniform temperature throughout the evaporator. The evaporator is maintained on what is commonly known as a defrosting cycle, the temperature of the coils being maintained by a suitable thermostatic control device alternately above and below the freezing point of water. When this method of 20 operation is utilized, no appreciable amount of frost is formed on the evaporator. It will be evident that the mean evaporator temperature is considerably higher than when a conventional or non-defrosting cycle below freezing is employed. 25 However, since the fan continuously circulates the air through the cooling unit and consequently throughout the chamber to be cooled, the temperatures in all parts of the chamber to be cooled are maintained substantially uniform, 30 and the temperature difference between the warmest part of the chamber to be cooled and the cooling unit, is relatively small. Since the evaporator units are all maintained at a substantially uniform temperature throughout, all 35 of the air passing through the casing 34 is uniformly cooled. If in the operation of this system a sudden increase in load is imposed, as by placing warm articles in the space to be cooled, the air circulated through the casing 34 will 40 transfer heat through the fins 31 and the sheets 45 28 to the refrigerant circulated in the tubes 24 and also to the negative heat storage substance or solution in the containers 30, which provides for simultaneous cooling by the refrigerant and negative heat storage substance. In this way a 50 high momentary peak capacity is obtained with a minimum capacity of the refrigerating system.

While I have shown and described my invention in connection with a compression refrigerating system, it will be understood that it is applicable to other types of refrigerating systems, and I do not desire my invention to be limited to the specific construction shown and described, and I intend in the appended claims to cover all modifications within the spirit and scope of my invention.

What I claim as new and desire to secure by Letters Patent of the United States, is:

65 1. A flooded evaporator for refrigerating systems comprising an upper header and a lower header, looped tubes connecting said headers, means including a conduit entering said lower header and having outlet tubes arranged in the 70 lower ends of said looped tubes for admitting liquid refrigerant to said unit and for inducing a flow of liquid refrigerant through said tubes from said lower header to said upper header, means for returning liquid refrigerant from said 75 upper header to said lower header, means for

maintaining said upper header partially filled with liquid refrigerant, and means for withdrawing gaseous refrigerant from said upper header.

2. A flooded evaporator for refrigerating systems having a header and a plurality of looped refrigerant circulating tubes connected to said header, means for maintaining said header partially filled with liquid refrigerant, a container surrounding each of said tubes and having walls 10 secured thereto, said container having a negative heat storage substance therein, a plurality of parallel heat-absorbing fins secured on said container, and means for directing circulating air longitudinally along said fins. 15

3. A flooded evaporator for refrigerating systems having an upper header and a lower header, a plurality of looped tubes connecting said headers, means injecting refrigerant into the lower ends of said tubes for inducing a flow 20 of liquid refrigerant from said lower header to said upper header, means for returning liquid refrigerant from said upper header to said lower header, a container surrounding each of said looped tubes, said container having side walls 25 in contact with both sides of said tubes and having a negative heat storage substance therein, and means for withdrawing vaporized refrigerant from said upper header.

4. A flooded evaporator for refrigerating systems having an upper header and a lower header, a plurality of looped tubes connecting said headers, means injecting refrigerant into the lower ends of said tubes for inducing a flow 30 of liquid refrigerant from said lower header to 35 said upper header, means for returning liquid refrigerant from said upper header to said lower header, a container surrounding each of said looped tubes, said container having walls in contact with both sides of said tubes and having 40 a negative heat storage substance therein, means for withdrawing vaporized refrigerant from said upper header, a casing surrounding said containers, and means for circulating air through 45 said casing over the surface of said containers.

5. A flooded evaporator for refrigerating systems having an upper header and a lower header, a plurality of looped refrigerant-circulating tubes connecting said headers, means including a conduit entering said lower header and 50 injecting refrigerant into the lower ends of said tubes for inducing a flow of liquid refrigerant from said lower header to said upper header, means for returning liquid refrigerant from said upper header to said lower header, 55 means for withdrawing vaporized refrigerant from said upper header, a container surrounding each of said looped tubes and having side walls secured in contact with said tubes, said container having a negative heat storage substance 60 therein, parallel zig-zag heat-absorbing fins secured to said containers, a casing surrounding said containers, and means for circulating air longitudinally of said fins through said casing 65 over the surfaces of said containers.

6. A cooling unit for refrigerating systems including a casing constituting an air duct, an evaporator including a plurality of refrigerant-circulating members having plates arranged within said casing, means including a wall of said casing having slots therein for supporting said plates, the edges of said plates entering said slots in said wall and being secured to said walls around said slots, and means for impelling air 70 75

through said air duct and between said members.

7. An evaporator for refrigerating systems comprising a header and a plurality of depending looped refrigerant-circulating tubes, flat containers surrounding said tubes and having a negative heat storage substance therein, a rib on the edge of each of said containers, and a casing surrounding said containers, said casing including upper and lower plates having elongated indentations therein transverse to said containers, said ribs and said plates being welded together at the indentations in said plates.

8. An evaporator for refrigerating systems having a plurality of refrigerant-circulating conduits, a casing surrounding said conduits, a flange on said casing, a removable end plate having a cylindrical housing thereon and resting on said casing against said flange, means for removably securing said plate to said casing, and means including a fan and a motor secured to said end plate for forcing circulating air through said casing.

9. A cooling unit for refrigerating systems including a casing having top, bottom, and side plates, an evaporator comprising a header and a plurality of refrigerant-circulating tubes arranged within said casing, an upwardly extending flange on said lower plate, a perforated end plate resting on said bottom plate adjacent said upwardly extending flange and provided with flanges engaging said side plates, means for removably securing said end plate flanges to said side plates, and means including a motor and a fan secured to said end plate for forcing circulating air through said casing.

10. A flooded evaporator for refrigerating systems, comprising an upper header and a lower header, looped tubes connecting said headers,

means including a second set of tubes arranged in the lower ends of said looped tubes for admitting liquid refrigerant to said unit and for inducing a flow of liquid refrigerant through said looped tubes from said lower header to said upper header, means including a passage for returning liquid refrigerant from said upper header to said lower header, means for maintaining said upper header partially filled with liquid refrigerant, and means for withdrawing gaseous refrigerant from 10 said upper header.

11. A flooded evaporator for refrigerating systems comprising an upper horizontal header and a lower horizontal header, looped tubes connecting said headers, means including a second set of tubes arranged in the lower ends of said looped tubes for admitting liquid refrigerant to said unit and for inducing a flow of liquid refrigerant through said looped tubes from said lower header to said upper header, means including a conduit 20 connecting said headers for returning liquid refrigerant from said upper header to said lower header, means for maintaining said upper header partially filled with liquid refrigerant, and means for withdrawing gaseous refrigerant from 25 said upper header.

12. A flooded evaporator for refrigerating systems having a header and a plurality of looped refrigerant circulating tubes connected to said header, means for maintaining said header partially filled with liquid refrigerant, containers surrounding each of said tubes and having walls secured thereto, said containers having a negative heat storage substance therein, a plurality of parallel heat absorbing fins secured on said 30 containers, a casing surrounding said containers, and means for directing circulating air through said casing longitudinally along said fins.

HARRY A. WHITESEL.
